Primary Examiner — Barbara Fox*Assistant Examiner* — Dana K Weiland(74) *Attorney, Agent, or Firm* — Strategic Patents, P.C.(57) **CLAIM**

The ornamental design for a display screen with graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a display screen with graphical user interface showing the new design;

FIG. 2 is a front view of a display screen with graphical user interface in a second embodiment;

FIG. 3 is a front view of a display screen with graphical user interface in a third embodiment;

FIG. 4 is a front view of a display screen with graphical user interface in a fourth embodiment;

FIG. 5 is a front view of a display screen with graphical user interface in a fifth embodiment; and,

FIG. 6 is a front view of a display screen with graphical user interface in a sixth embodiment.

The broken lines shown in the drawings represent portions of the display screen with graphical user interface and form no part of the claimed design.
